UNITED STATES PATENT OFFICE.

HAROLD IRWIN, OF TIKOKINO, NEW ZEALAND.

ALARM.

No. 883,025.

Specification of Letters Patent. Patented March 24, 1908.

Application filed May 1, 1907. Serial No. 371,224.

To all whom it may concern:

Be it known that I, HAROLD IRWIN, a subject of the King of Great Britain, and a resident of Tikokino, New Zealand, have invented 5 a new and Improved Alarm, of which the following is a full, clear, and exact description.

The invention relates to alarms for scaring birds and for other purposes, and its object 10 is to provide a new and improved alarm, which is simple and durable in construction, cheap to manufacture, and arranged to sound alarms by periodic explosions of fire crackers and like detonating devices.

15 The invention consists of novel features and parts and combinations of the same, which will be more fully described herein-after and then pointed out in the claims.

A practical embodiment of the invention 20 is represented in the accompanying drawings forming a part of this specification, in which similar characters of reference indicate corresponding parts in all the views.

Figure 1 is a side elevation of the improvement; Fig. 2 is a sectional plan view of the same on the line 2—2 of Fig. 1, and Fig. 3 is a sectional side elevation of the same.

The improved alarm is mounted in a suitably constructed casing A, provided with a 30 removable cover B and with a hopper-shaped bottom C discharging into an explosion receptacle D, preferably of open wire mesh, and removably attached at its upper end to hooks E arranged on the outside of the casing A at the base thereof, as plainly indicated in the drawings. Within the casing A is secured a spider or other frame work F supporting a spirally arranged support G, carrying at intervals U-shaped hooks or forks H, 40 into which is placed a slow burning fuse I of any approved construction. On the hooks H are tied or otherwise secured the fuses J' of fire crackers or like detonating devices J, which are thus suspended within the casing 45 A with their fuses J' in contact with the slow burning main fuse I. By arranging the slow burning fuse in the manner described a large number of independently supported fire crackers or like detonating devices J may be used in one apparatus. Now it is evident that 50 when the slow burning fuse I is ignited at one end it finally reaches the fuse J' of the first fire cracker J, and consequently this fire cracker fuse is ignited and burns, and in so doing becomes detached from the hooks H and drops down into the hopper C, and from

the latter down into the bag D, in which the fire cracker finally explodes through the medium of its burning fuse. The slow burning main fuse I finally reaches the fuse of the 60 next fire cracker, and so on, until all the fire crackers are detached and their fuses ignited, as above explained, the detached fire crackers with their ignited fuses dropping down into the receptacle D to be exploded therein. 65 Now as the main fuse I burns very slowly, it is evident that the fire crackers or detonating devices J are exploded in the receptacle D at stated intervals, and consequently the apparatus forms a very serviceable alarm 70 for scaring birds from fields. It will also be seen that the device may be used in places in which like periodic alarms are desired.

The casing A is provided at one side with a bracket K for conveniently attaching it to 75 a post or other support, with a view to hold the apparatus a desired distance above the ground.

As the explosion receptacle D is of an open mesh or perforate material it allows free escape 80 of the smoke and fumes arising from the exploding detonating devices, and at the same time the receptacle prevents any portions of the exploded fire crackers or detonating devices from scattering over the surroundings, thus preventing flying fragments 85 from setting fire to the surroundings.

By having the hopper-shaped bottom C any ignited portions of the exploded fire crackers are prevented from passing upwards 90 into the casing and prematurely igniting the crackers suspended therein.

Having thus described my invention, I claim as new and desire to secure by Letters Patent:

1. An alarm comprising a casing provided with a removable cover, and a hopper-shaped bottom, a perforate explosion chamber detachably connected with the casing and into which the hopper discharges, a spider within the casing provided with a plurality of U-shaped hooks, a main fuse supported by the hooks, and a plurality of detonating devices having their fuses connected with the hooks and contacting with the main fuse. 95

2. An alarm comprising a slow burning fuse, means for supporting the same, suspended detonating devices having fuses, each of the latter being in contact with the said slow burning fuse, the latter on burning successively igniting the fuses of the said 110

detonating devices to successively detach the latter, the detached detonating device being set off by its own burning fuse, a casing having a hopper-shaped bottom and containing the said slow burning fuse and the said detonating devices, and an open mesh receptacle hung on the said casing and into which discharges the said hopper.

3. An alarm comprising a casing having a hopper-shaped bottom, an explosion chamber into which discharges the said bottom, a spirally arranged support within the said casing and carrying spaced hooks for sup-

porting a main slow burning fuse, and detonating devices having fuses each secured to 15 one of the said hooks and in contact with the said main fuse.

In testimony whereof I have signed my name to this specification in the presence of two subscribing witnesses this 26th March 20 1907.

HAROLD IRWIN.
